(57) **CLAIM**

The ornamental design for a mini heat press as shown and described.

DESCRIPTION

FIG. 1 is a perspective view of a part of mini heat press showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a perspective view of another part of mini heat press showing my new design;

FIG. 10 is another perspective view thereof;

FIG. 11 is a front view thereof;

FIG. 12 is a back view thereof;

FIG. 13 is a left view thereof;

FIG. 14 is a right view thereof;

FIG. 15 is a top plan view thereof;

FIG. 16 is a bottom plan view thereof;

FIG. 17 is a perspective view of a mini heat press showing my new design, in a combined state;

FIG. 18 is a partial enlarged view of portion 18 in FIG. 1;

FIG. 19 is a partial enlarged view of portion 19 in FIG. 9;

and,

FIG. 20 is a partial enlarged view of portion 20 in FIG. 10.

The broken lines depict portions of the mini heat press and

form no part of the claimed design.

1 Claim, 20 Drawing Sheets
